US0D1110627S

(12) **United States Design Patent** (10) **Patent No.:** **US D1,110,627 S**
(45) **Date of Patent:** **** Jan. 27, 2026**

(54) **FLOOR WASHING APPLIANCE**

(71) Applicant: **Beijing Roborock Technology Co., Ltd.**, Beijing (CN)

(72) Inventors: **Xin Li**, Beijing (CN); **Lan Huang**, Beijing (CN); **Zechen Yu**, Beijing (CN)

(73) Assignee: **Beijing Roborock Technology Co., Ltd.**, Beijing (CN)

(**) Term: **15 Years**

(21) Appl. No.: **35/521,376**

(22) Filed: **May 24, 2024**

(80) **Hague Agreement Data**

Int. Filing Date: **May 24, 2024**

Int. Reg. No.: **DM/237644**

Int. Reg. Date: **May 24, 2024**

Int. Reg. Pub. Date: **Jun. 21, 2024**

(30) **Foreign Application Priority Data**

Nov. 27, 2023 (CN) 202330777744.4

(51) **LOC (15) Cl.** **15-05**

(52) **U.S. Cl.**

USPC **D32/22**

(58) **Field of Classification Search**

USPC D32/1, 15-25, 32-35, 38, 39
